UNITED STATES PATENT OFFICE

2,335,160

FLEXWOOD SPRING FOR CHAIR SEATS

Alvin J. Schaffner, Aurora, Ill., assignor to Kroehler Mfg. Co., Naperville, Ill., a corporation of Illinois

Application December 30, 1942, Serial No. 470,552

2 Claims. (Cl. 155—179)

This invention relates to a laminated flexwood spring for chair seats, and has for its principal object to provide a novel and improved leaf spring construction made of laminated flexwood which may be readily applied to a chair seat and which will give to said seat the required resilient flexibility heretofore provided by the use of steel coiled or other steel springs.

A further object of the invention is to provide a flexwood spring construction for chairs affording a greater range or degree of flexibility than is attained by spring arrangements of a somewhat similar character heretofore proposed. More particularly, the present invention constitutes an improvement in some respects over the construction disclosed and claimed in my co-pending application, Serial No. 443,249, filed May 16, 1942, which has resulted in Patent No. 2,316,628, issued April 13, 1943.

The advantages of the invention will appear more fully as I proceed with my specification.

In the drawings:

Figure 1 is a perspective view of a chair of any familiar construction, with the upholstered seat containing the improved flexwood spring of the invention.

Figure 2 is an enlarged vertical section in a plane indicated by the line 2—2 of Figure 1, with the upholstery of the seat removed.

Figure 3 is a fragmentary perspective view of the chair frame showing the lower spring unit attached thereto.

Figure 4 is a perspective view showing both the upper and lower spring units removed from the chair frame.

Figure 5 is a fragmentary top plan view showing one end of the chair frame with both spring units applied thereto.

Figure 6 is a front view of the chair frame with parts broken away to show the spring units in assembled relation therein.

Referring now to the embodiment of the invention illustrated in the drawings, Figure 1 shows an upholstered chair having a frame made of wood in the usual manner. 12 indicates the front rail, and 13, 13 the side rails of the frame. The rear ends of the side rails 13 are connected by a horizontal frame member 14 adjacent the bottom of the frame. The frame may also include a pair of upstanding front corner posts 15, 15 and rear corner posts 16, 16 which are connected by upper side rails 17, 17 spaced slightly above the side rails 13, 13. A cross bar 18 is connected between the rear ends of the upper side rails 17, 17 adjacent the rear up-

right posts 16 so as to be parallel with, but spaced substantially above, the first named frame member 14. A pair of upright back supports 19, 19 may also be secured along the inner faces of the rear upright supports 16, 16, in the form shown said upright back supports having their lower ends connected to the cross bar 18, as shown in Figure 3.

I also provide a plurality of upright guide members 20, 20 disposed in laterally spaced relation with each other so as to form a plurality of upright slots in the space formed between the lower rear frame member 14 and the cross bar 18 at the rear end of the frame. In the form shown herein, said guide members 20, 20 have their upper ends connected to a cross bar 21 having its ends suitably secured in the frame as by connection to the upright back supports 19, 19 immediately above the cross bar 18 (see Figures 2 and 3). The purpose of the slots between these upright guide members will presently appear.

The spring structure of my invention is preferably made up of two separate units, the lower spring unit being indicated generally at 23, and the upper unit being indicated generally at 24. The lower spring unit 23 consists of a plurality of laterally spaced, parallel flexible spring leaves 25 attached at their front ends to an anchor bar 26 and curving upwardly and then rearwardly toward their rear ends, which are guided for relatively free vertical movement in the slots formed between the upright guide members 20 at the rear end of the frame. The anchor bar 26 is rigidly connected to the chair frame as by securing its opposite ends to the inner surfaces of the side rails 13, 13 at a suitable point toward the front of the chair. The lower spring unit may therefore be more or less permanently mounted in the chair frame. In connection with the lower spring unit, I also provide an auxiliary support bar 27 spaced rearwardly and below the level of the anchor bar 26 in position to be engaged by the spring leaves 25, 25 when said spring leaves are placed under tension.

The upper spring unit comprises a plurality of laterally spaced, parallel, flexwood spring leaves 30 attached at their front ends to a depending rocker bar 31 which extends transversely of and depends below said leaves. The spring leaves 30 of the upper unit correspond in number with the spring leaves 25 of the lower unit. The leaves 30 are arched upwardly intermediate their ends, and their rear ends are adapted to be disposed upon and engage the free ends of the leaves 25 of the

lower spring unit in the slots formed between the upright guide members 20, 20, as shown in Figure 2.

The upper spring unit is completed by a plurality of laterally spaced, parallel, flexwood spring leaves 32, each of which is secured at its rear end on the upwardly arched, intermediate portion of one of the spring leaves 30, and with its forward end curved upwardly and attached to a strip 33 extending transversely across the front of the upper spring unit.

The front rail 12 of the chair seat is provided along its upper edge with a rounded groove 35 in which seats the rocker bar 31, which has a correspondingly transversely rounded bottom edge. The upper spring unit 24 as thus described may be assembled or disassembled as a unit in the chair frame by inserting the rear ends of the spring leaves 30 in the upright slot formed between the guide members 20 at the rear of the frame, and resting on the corresponding rear ends of the spring leaves 25 of the lower spring unit 23. The rocker bar 31 is fitted in the grooves 35 of the front rail 12, as shown in Figure 2.

Suitable upholstering material may be applied along the upper surface of the upper spring unit 24 in any suitable manner, as indicated in Figure 1.

It will be understood that straight grain woods and semi-flexible waterproof glue may be used in the manufacture of the laminated spring leaves. They are given the required form or shape and are so treated in a familiar manner that when finished they maintain their shape and form equally as well as similar springs manufactured from steel.

Although I have shown and described one particular embodiment of my invention, it will be understood that I do not wish to be limited to the exact construction shown and described, but that various changes and modifications may be made without departing from the spirit and scope of my invention as defined in the appended claims.

I claim as my invention:

1. A flexwood spring construction comprised of upper and lower units, the lower unit comprising a plurality of laterally spaced flexwood spring leaves having their forward ends connected to an anchoring member, and their rear ends being relatively free, the upper unit having a like number of laterally spaced flexwood spring leaves arched upwardly intermediate their ends, the front ends of said arched leaves being fixed to a depending rocker bar, and the rear ends of said arched leaves being adapted to rest on the corresponding leaves of the lower spring unit, said upper unit also having a plurality of spring leaves, each of which is secured at its rear ends on the upwardly arched intermediate portion of one of said arched spring leaves, and with its forward end attached to a transverse strip defining the upper front edge of said upper spring unit.

2. A flexwood spring construction comprising an upper frame having front and back rails, upper and lower spring units comprising a plurality of laterally spaced flexwood spring leaves having their forward ends connected to a transverse anchoring member fixed on said frame, and their rear ends being relatively free, the upper unit having a like number of laterally spaced flexwood spring leaves arched upwardly intermediate their ends, the front ends of said arched leaves being fixed to a depending rocker bar, and the rear ends of said arched leaves being adapted to rest on the corresponding leaves of the lower spring unit, said upper unit also having a plurality of spring leaves, each of which is secured at its rear ends on the upwardly arched intermediate portion of one of said arched spring leaves, and with its forward end attached to a transverse strip defining the upper front edge of said upper spring unit, and said back rail being provided with upright laterally spaced slots through which the rear ends of the leaves of both the upper and lower spring units extend for relatively free vertical movement.

ALVIN J. SCHAFFNER.
